UNITED STATES PATENT OFFICE

GUY M. HARTSOCK, OF SOUTH BEND, INDIANA, ASSIGNOR TO THE STUDEBAKER CORPORATION, OF SOUTH BEND, INDIANA, A CORPORATION OF NEW JERSEY

BRAKE

Application filed August 3, 1929. Serial No. 383,186.

This invention relates to brake shoes and particularly to shoes of the internal expanding type, the principal object being to form a brake shoe from a single piece of metal to provide the same with an arcuate lining supporting portion and a pair of radial reinforcing webs converging toward each other.

Another object is to provide a brake shoe comprising an arcuate portion and a pair of radial reinforcing webs inclined toward each other and having their free edges in contact with each other, the webs forming the sole reinforcing means for the arcuate portion.

A further object is to provide a brake shoe comprising an arcuate portion and a pair of reinforcing webs forming the sole radial reinforcing means for the arcuate portion, openings being provided in the webs to permit the securing of the brake lining to the arcuate portion.

A further object is to provide a brake shoe comprising an arcuate portion and a pair of converging radial reinforcing webs forming the sole radial reinforcing means for the arcuate portion, a journal bushing being extended through and secured to the webs to provide an anchoring means for the shoe.

A further object is to provide a brake shoe comprising an arcuate portion and a pair of converging radial reinforcing webs forming the sole reinforcing means for the arcuate portion, the metal at one end of the webs being folded into overlapping relationship and into contact with the ends of the webs to provide a support for a cam contact member.

These being among the objects of the present invention, the same consists of certain features of construction and combination of parts to be hereinafter described with reference to the accompanying drawing and then claimed having the above and other objects in view.

In the accompanying drawing which illustrates a suitable embodiment of the present invention,

Figure 1 is a side elevation of the brake shoe showing the brake lining attached thereto.

Figure 2 is an enlarged sectional view taken on the line 2-2 of Figure 1.

Figure 3 is an enlarged sectional view taken on the line 3-3 of Figure 1, showing the journal bushing secured in the converging webs.

Figure 4 is an end view of the brake shoe looking in the direction of the arrows 4-4 of Figure 1, showing the cam contact member secured thereto.

Figure 5 is an enlarged fragmentary side elevational view showing the ends of the webs in folded position and the cam contact member secured thereto.

Referring to the accompanying drawing in which like numerals refer to like parts throughout the several views, the brake shoe comprises a brake lining receiving portion 10 formed to conform with a brake drum (not shown) with which the shoe is adapted to engage. The free edges of the arcuate portion 10 are bent over to form radial reinforcing webs 11, bent so that the free edges thereof are adapted to contact with each other, the same being welded together at 12 if so desired. Although it is preferable to weld the webs 11 along the free edges at 12, in some forms and sizes of brake shoes, this operation may not be necessary and my invention is not limited to this detail.

The arcuate portion 10 is formed and adapted to receive a brake lining 13. In order that the brake lining 13 may be secured to the arcuate portion 10, I preferably form openings 14 in the webs 11 and the metal forming the tabs 15 cut from the openings 14 is preferably folded into contact with the under face of the arcuate portion 10 to provide reinforcements for the rivet 16 extending through the brake lining 13 and the arcuate portion 10 for securing the brake lining 13 thereto.

The metal at one end of the webs 11 is preferably folded as is clearly shown in Figures 4 and 5, as at 17 and 18, to provide a support for the cam contact member 19 which may be riveted, bolted, welded or otherwise secured to the end face of the brake shoe. Adjacent to the end of the brake shoe opposite the cam contact member 19, I pro-

vide a journal bushing 20 extending through the converging webs 11 to provide a pivot for the anchor pin. The journal bushing 20 is preferably secured in the webs 11 by 5 welding the same thereto as at 21.

From the foregoing description it is readily apparent that a brake shoe is provided which requires the minimum amount of material, which is rigid in construction, light 10 in weight and economical to manufacture. It is further apparent that the arcuate lining supporting portion is formed with radial reinforcing webs forming the sole radial reinforcing means therefor, which webs are integral therewith thereby tending to give 15 added strength and rigidity to the brake shoe structure.

Formal changes may be made in the specific embodiment of the invention described 20 without departing from the spirit and substance of the particular invention, the scope of which is commensurate with the appended claims.

What I claim is:

- 25 1. A brake shoe comprising a pressed metal member having an arcuate portion and webs integral with and extending radially from the outer edges of said arcuate portion, said radial webs converging toward and contacting with each other at their free edge, and a journal bushing extending through said converging webs.
- 30 2. A brake shoe comprising a pressed metal member having an arcuate portion, and integral converging radially extending webs, portions of the metal of said radial webs being cut from said webs and folded inwardly to permit securing means for a brake lining to be inserted through said arcuate 35 portion.
- 40 3. A one piece brake shoe comprising an arcuate portion and converging radially extending reinforcing webs, the metal at one end of said webs being folded against the 45 end face thereof to provide a Y-shaped contact for a cam contact member, and a journal bushing extending through said radial webs adjacent to the end opposite said cam contact member.
- 45 4. A brake shoe comprising, a pressed metal member having an arcuate portion, and integral radially extending webs converging and contacting with each other at their free edges, said webs having openings formed 55 therein permitting the securing of a brake lining on said arcuate portion, the metal cut out of the webs to form said openings being folded against the arcuate portion to provide reinforcement for the brake lining securing 60 means.

Signed by me at South Bend, Indiana this 31st day of July 1929.

GUY M. HARTSOCK.
